(57) CLAIM

The ornamental design for safety tape having illuminating regions, as shown and described.

DESCRIPTION

FIG. 1 is a front view of safety tape having illuminating regions showing my new design, wherein the illuminating regions are not illuminated;

FIG. 2 is another front view thereof, wherein the illuminating regions are not illuminated and unclaimed portions of the safety tape having illuminating regions are shown in an alternate orientation;

FIG. 3 is a front view thereof, wherein the illuminating regions are in an illuminated state;

FIG. 4 is another front view thereof, wherein the illuminating regions are in an illuminated state and unclaimed portions of the safety tape having illuminating regions are shown in an alternate orientation;

FIG. 5 is an enlarged right side view, wherein the illuminating regions are not illuminated, the left side view being a mirror image thereof; and,

FIG. 6 is an enlarged right side view, wherein the illuminating regions are in an illuminated state, the left side view being a mirror image thereof.

The broken line showing of portions of the safety tape having illuminating regions forms no part of the claimed design.
